ABSTRACT

A shelving rack system, having at least two divider supports extending across the bottom of a base, with a support panel positioned on top of the base, wherein the dividers are positionable from side-to-side to vary the width of the product dispensing channels between the dividers in the shelving rack. Each divider has legs that pass through holes in both an optional support panel and the divider supports.

FIG. 5

FIG. 6

FIG. 7

FIG. 8

SHELVING RACK HAVING BOTTOM SUPPORT PANEL WITH MOVEABLE DIVIDERS

RELATED APPLICATION

The present application is a Continuation of U.S. patent application Ser. No. 15/979,233, filed May 14, 2018, of same title, the full disclosure of which is incorporated herein by reference in its entirety.

TECHNICAL FIELD

The present system relates in general to wire shelving units and in particular to wire shelving units for dispensing products such as milk and beverages from refrigerated store cabinets.

SUMMARY OF THE INVENTION

The present system provides a shelving rack system, comprising: a wireframe base; at least two divider supports extending across the bottom of the wireframe base; an optional support panel positioned on top of the wireframe base; and a plurality of dividers positioned on top of the support panel, wherein each divider has at least two legs, and each leg passes through a hole in the optional support panel and down into a hole in one of the divider supports. The dividers are preferably made of a lightweight material. The optional support panel is preferably made of a low-friction material.

The divider supports extend underneath the bottom of the wireframe base from one side of the wireframe base to the other, and the dividers extend from the back to the front of the shelving rack (above the wireframe base). Thus, the divider supports and the dividers are generally perpendicular to one another. This allows the dividers to be supported perpendicularly at many places along their lengths.

The holes in the optional support panel are positioned above the holes in the divider supports. Placing the legs of the dividers through the holes in the optional support panel and into the holes in the divider supports holds the dividers in position above the optional support panel. In addition, placing the legs of the dividers through the holes in the optional support panel also secures the optional support panel in position under the products being dispensed. An advantage of the present system is that the dividers are easily moveable side-to-side such that the side-to-side spacing between parallel dividers is adjustable. As such, the dividers can be positioned at various distances apart from one another that correspond to the widths of the products being dispensed. For example, the dividers can be positioned closer together when narrow cans of soda are positioned thereon, or farther apart when wider gallon jugs of milk are to be dispensed.

One advantage of the present shelving rack is the fact that the spacing between the dividers is quickly and easily adjustable. This is due to the fact that there are more sets of aligned holes in the optional support panel and divider supports than there are dividers being used. As such, the dividers can easily be moved from one position to another.

Another advantage of the present system is that the flat optional support panel underneath the products being dispensed reduces the total number of wires required in the wire frame below the support panel. This is due to the fact that the products being dispensed are supported by the optional flat support panel, rather than simply resting on a wire grid. As

such, the wires of the wire grid (i.e. wire base) can be positioned farther apart from one another, and the support panel can be made of a low friction material.

Optionally, the present system also includes a back support (such as a wire) spanning across the back ends of the dividers, and optional bottom legs for positioning the support rack in a cabinet. These and other mechanisms for attaching the present system to a cabinet are all contemplated, all keeping within the scope of the present invention.

BRIEF DESCRIPTION OF THE DRAWINGS

FIG. 1 is a rear perspective view of the present shelving rack system.

FIG. 2 is a side elevation view of the present shelving rack system.

FIG. 3 is a top plan view of the present shelving rack system.

FIG. 4 is a close-up detail view of the leg of the divider passing through the holes in the support panel and through the holes in the divider supports.

FIG. 5 is a close-up top plan view corresponding to FIG. 1, with a section of the support panel removed, showing the wire frame structure therebelow.

FIG. 6 is a close-up of an optional divider that accepts thick and thin front stops.

FIG. 7 is a close-up of an optional front bracket attached to the present shelving rack system.

FIG. 8 is a bottom plan view of the present shelving rack system.

DETAILED DESCRIPTION OF THE DRAWINGS

The present shelving rack system is seen in FIGS. 1 to 3, as follows.

Shelving system 10 comprises: a wireframe base 20; at least two divider supports 30 extending across the bottom of wireframe base 20; an optional support panel 40 positioned on top of wireframe base 20; and a plurality of dividers 50 positioned on top of optional support panel 40, wherein each divider 50 has at least two legs 52, and each leg 52 passes through a hole 41 in optional support panel 40 and also passes down into a hole 31 in one of divider supports 30. Holes 41 and 31 can be of any shape, as desired. Legs 52 can also be of any shape and may either be formed as part of the divider 50 or welded to the divider. In addition, the bottom end of leg 52 can be projection thereon such that once divider 50 is moved to insert the opposite leg into the divider 50, the rear of the divider 50 cannot be lifted.

In optional embodiments of the present system, optional support panel 40 is omitted, and product can be placed directly upon wireframe base 20. In further optional embodiments, base 20 is not made of wireframe materials, but is instead made of other suitable materials. As such, the present system is not limited only to wireframe embodiments. As can also be seen, dividers 50 preferably extend from the back 21 to the front 22 of wireframe base 20. Optionally, wireframe base 20 can comprise bottom legs 25 for positioning the support rack in a cabinet.

Preferably, as best seen in FIG. 8, wireframe base 20 comprises both: parallel wireframe bars 24 extending from the back to the front of the wireframe base; and parallel wireframe bars 26 extending from one side of the wireframe base to the other side of the wireframe base.

As seen in the close-up view of FIG. 4, divider supports 30 are positioned below the bottom of wireframe base 20, and holes 41 in optional support panel 40 are positioned

above the holes 31 in the divider supports. As such, legs 52 lock the optional support panel 40 into a secure position on top of wireframe base 20.

As seen in the close-up view of FIG. 5, divider supports 30 extend from one side of wireframe base 20 to the other side of wireframe base 20. Thus, dividers 50 extend in a perpendicular direction to divider supports 30. Preferably, as best seen in FIG. 2, each divider 50 comprises parallel horizontal bars 54 and optional parallel vertical bars 56 to strengthen the dividers 50 vertically.

As can be appreciated, dividers 50 are individually positionable between a plurality of different parallel side-to-side positions such that the side-to-side spacing between parallel dividers can be adjusted as desired. This re-positioning of individual dividers 50 is done by simply moving legs 51 from one hole 31 to another hole 31 in divider supports 30.

Preferably, the parallel wireframe bars 24 extending from the back to the front of the wireframe base 20 are spaced farther apart than the spacing between dividers 50.

As seen in FIGS. 6 and 7, an optional front stop 60 spans across the front ends of dividers 50. As can be seen, the optional front stop 60 can simply be a wire that passes through divider 50 (at point 61), or a wire that passes through an optional front bracket 65 (at point 66). As seen in FIG. 7, front bracket 65 can optionally have small holes 68 for passing a slender wire therethrough, or larger holes 69 for passing a bar therethrough. Moreover, these various round and square apertures can be positioned at different heights, as illustrated. Additionally, the front stops 60 and their accompanying holes can be of any size or shape, as desired.

What is claimed is:

1. A shelving rack system, comprising:

a wireframe base, wherein the wireframe base comprises a length, a width, a plurality of first parallel bars extending from a back to a front along the length of the wireframe base, and a plurality of second parallel bars extending from a left side to a right side of the wireframe base along the width of the wireframe base, wherein the second parallel bars are perpendicular relative to the first parallel bars forming a grid pattern; at least two divider support strips extending substantially across the entire width of the wireframe base, wherein each divider support strip is underneath the wireframe

base and each divider support strip has a plurality of apertures therein, the apertures extending substantially across the entire width of the wireframe base, wherein each divider support strip is spaced apart from each other; wherein each divider strip has a proximal end attached to a bottom of the wireframe base, a distal end spaced apart from the wireframe base, and an inclined portion between the proximal end and the distal end of each divider strip;

a plurality of dividers positioned on top of the wire frame base, wherein each divider has at least two legs, and each leg passes both through a corresponding hole in one of the divider support strips; and wherein the number of divider legs is less than the number of apertures in each divider support strip.

2. The shelving rack system of claim 1, wherein the dividers extend in a direction generally parallel to the first parallel bars of the wireframe base.

3. The shelving rack system of claim 1, wherein the dividers extend in a perpendicular direction to the divider support strips.

4. The shelving rack system of claim 1, wherein the dividers are parallel to each other.

5. The shelving rack system of claim 1, wherein the dividers are each individually positionable between a plurality of parallel positions such that a spacing between a corresponding pair of adjacent dividers from said plurality of dividers is adjustable.

6. The shelving rack system of claim 1, further comprising:

a front stop spanning across front ends of the dividers.

7. The shelving rack system of claim 6, wherein the front stop is a wire that passes through front brackets of corresponding dividers from said dividers respectfully.

8. The shelving rack system of claim 1, further comprising:

a support panel positioned on top of the wireframe base.

9. The shelving rack of claim 8, wherein the support panel has a plurality of apertures passing therethrough and wherein the divider legs pass through the apertures in the support panel such that the divider legs lock the support panel into a secure position on top of the wireframe base.
